Patented Jan. 14, 1969

213,237

PIECE GOODS HANGER

Irwin Bassett, North Woodmere, N.Y., assignor to The Lampert Company, Inc., New York, N.Y., a corporation of New York

Filed Jan. 19, 1968, Ser. No. 10,234

Term of patent 14 years

U.S. Cl. D80—8
Int. Cl. D6—07

FIG. 1

FIG. 2

FIG. 3

FIG. 1 is a top plan view of a piece goods hanger embodying my new design;

FIG. 2 is a side elevational view thereof;

FIG. 3 is an end elevational view thereof.

The broken line representation of a piece of merchandise in FIGS. 2 and 3 is for purposes of illustration only.

I claim:

The ornamental design for a piece goods hanger, as shown and described.
